Patented Aug. 24, 1920.

FIG. 1

FIG. 2

FIG. 3

INVENTOR
WILLIAM M. SIMPSON
BY C. T. ALLEN
ATTY

UNITED STATES PATENT OFFICE.

WILLIAM M. SIMPSON, OF PORTLAND, OREGON, ASSIGNOR OF ONE-HALF TO WOO LAI SUN, OF PORTLAND, OREGON.

WASHING-MACHINE.

1,351,008.

Specification of Letters Patent. Patented Aug. 24, 1920.

Application filed May 27, 1919. Serial No. 300,217.

To all whom it may concern:

Be it known that I, WILLIAM M. SIMPSON, a citizen of the United States, residing at Portland, county of Multnomah, State of Oregon, have invented certain new and useful Improvements in Washing-Machines, of which the following is a specification.

My invention relates to washing machines in general, and particularly to such machines as are adapted to the washing of dishes, and the object of my invention is to provide a simple cheap form of such a machine adaptable for hotels, restaurants and the like.

I accomplish the above object by means of the construction illustrated in the accompanying drawing, which is a part of this application for Letters Patent, like characters of reference indicating like parts throughout the several views thereof, and in which:

Figure 1 is a side elevation, partially sectioned, of my device.

Fig. 2 is a side elevation of a modified form of my device.

Fig. 3 is a fragmentary sectional elevation of a further modification of my device.

In general my device consists of an oscillatable container having pumping devices in each end thereof adaptable to keep liquid therein in constant reciprocating motion among the dishes contained therein.

The container 4 is supported upon trunnions 5 oscillatably mounted in bearing stands 6, and a cover 7 is provided for each container through which to enter the dishes.

At each end of the container 4 is mounted an inwardly dished perforated diaphragm 8, the ends of the container being closed by a solid diaphragm 9 mounted outside diaphragm 8, said diaphragm 9 being of flexible material such as thin metal, rubber, leather, or the like.

A housing 10 is mounted upon each end of the container 4 and a shaft 11 is mounted within a hub 12 upon said housing, said shaft being axially aligned with said container 4 and attached to the solid diaphragm 9, as shown in Fig. 1.

Levers 13 are pivotally attached to shafts 11, and above such pivotal attachment point are pivotally connected by a link 14.

In the construction shown in Fig. 1 each lever 13 is mounted at its lower end in a diagonally slotted bracket 15 by means of

a cross pin 16, and each lever 13 is provided at its upper end with a handle.

In use, the dishes are placed in the container 4 through the cover 7, and the container partially filled with soapy water, and the cover 7 closed.

Reciprocal operation of either lever 13 now causes simultaneous distortions of diaphragms 9, one outward and the other inward relatively to container 4, which causes the water to be sucked through the perforations of one of diaphragms 8 and forcibly expelled through the perforations in the other diaphragm 8, thus causing a reciprocating current of water within the container 4 and also numerous forced streams or jets of water from the perforations in diaphragms 8.

To further assist in the washing process oscillation of the container 4 is provided for, since operation of the levers 13 will cause the pins 16 to slide within the diagonal slots of the brackets 15, one ascending while the opposite descends, thus causing the oscillation of container 4, as shown in dotted center lines in Fig. 1.

Air ports 17 are provided in housings 10 to allow air to enter and leave the same as the diaphragm 9 reciprocates.

In the modified form of construction shown in Fig. 2 the interior arrangements of the container 4' are identical with that shown in Fig. 1, but the oscillation of the container is provided for by mounting the container upon a rocker 18 operating upon a base 19, a single handle lever 20 being pivotally attached to the container and pivotally connected to each of the levers 13' by links 21', the levers 13' being pivotally fulcrumed at the lower ends thereof to brackets 22 secured to container 4'.

In the modification shown in Fig. 3 a reciprocating piston 23 is mounted within a cylinder 24 upon housing 10', and said piston connected to the shaft 11', this piston taking the place of the diaphragm 9 of Fig. 1.

My invention may be made of any size and constructed of any materials deemed convenient and suitable for a device of this character, and while I have illustrated and described a form of construction and arrangement of parts found desirable in materializing my invention, I wish to include in this application for Letters Patent all

mechanical equivalents and substitutes that may fairly be considered to come within the scope and purview of my invention as defined in the appended claims.

Having disclosed my invention so that others may be enabled to construct and to use the same, what I claim as new, and desire to secure by Letters Patent is:

1. In a washing machine: a container; 10 perforated diaphragms at each end of said container; housings upon each end of said container outside said perforated diaphragms; reciprocating shafts mounted within said housings; pumping means upon 15 the inner ends of said shafts; levers connected to the outer ends of said shafts; and means whereby the operation of said levers will oscillate said container.
2. In a washing machine: a container; a 20 perforated diaphragm at each end of said container; housings at each end of said con-

tainer outside of said perforated diaphragm; a flexible diaphragm mounted transversely of said container between each of said perforated diaphragms and the adjacent housing; a shaft reciprocatingly mounted within each of said housings and attached to the adjacent flexible diaphragm; a reciprocatingly-mounted lever attached to the outer end of each of said shafts; a link 30 connecting said levers; and means whereby the operation of said levers may oscillate said container.

In witness whereof I claim the foregoing as my own, I hereunto affix my signature 35 in the presence of two witnesses, at Portland, county of Multnomah, State of Oregon, this 6th day of May, 1919.

WILLIAM M. SIMPSON.

Witnesses:

C. F. BLAKE,
L. J. ROBINSON.
